UNITED STATES PATENT OFFICE.

CHARLES EDWIN BLUE, OF WHEELING, WEST VIRGINIA.

MACHINE FOR THE MANUFACTURE OF GLASSWARE.

SPECIFICATION forming part of Letters Patent No. 684,669, dated October 15, 1901.

Application filed August 4, 1900. Serial No. 25,898. (No model.)

To all whom it may concern:

Be it known that I, CHARLES EDWIN BLUE, a citizen of the United States, residing at Wheeling, in the county of Ohio and State of West Virginia, have invented new and useful Improvements in Machines for the Manufacture of Glassware, of which the following is a specification.

My invention relates to improvements in machines for the manufacture of glassware, and pertains to providing means for delivering a predetermined quantity of molten glass to the forming mechanism at each charge thereof, all of which will be fully described hereinafter.

In the accompanying drawings, Figure 1 is a side elevation of a machine embodying my invention, partly shown in vertical section, the parts being shown in a charging position. Fig. 2 is an end elevation of the same, being shown partly in section and in a pressing position. Fig. 3 is a top sectional plan on the line 3 3 of Fig. 1. Fig. 4 is a detail view, partly in section, of the bottom for the weighing-receptacle. Fig. 5 is a detached view of the latch for locking together the two parts of the bottom of the weighing-receptacle.

Referring now to the drawings, A is a supporting-table of any desired form, from which projects a vertical standard 1. Vertically movable in relation to this standard in suitable bearings is a plunger-rod 15, carrying a suitable presser-head of any desired form and a plunger 14 at its lower end. The plunger is movable vertically through the medium of a counterweighted lever 16 and a link 17, having its ends connected, respectively, with the said plunger-rod and lever.

The mold 13 may be of any desired form, and the plunger or coacting member 14 is adapted to coact therewith for forming the article or for forming a blank to be afterward finished.

Located above the mold 13 is a weighing-receptacle 4, which is rigid with a suitable trunnion 9, having vertical journals in suitable supports α , projecting from the lower end of the standard 1. By means of this trunnion connection the weighing-receptacle is laterally movable in respect to the mold for the purpose of permitting the coacting member or plunger 14 entering the mold 13.

The bottom 5 of the weighing-receptacle 4 is made in two parts, as illustrated in Fig. 4, and adapted to swing horizontally for the purpose of opening the bottom of the weighing-receptacle to permit the weighed glass to drop into the mold therebelow. The two parts of the bottom are locked together through the medium of a latch b , adapted to engage the handles thereof. The inner end of the bottom 5 is pivoted at the point 8, and a scale-beam 10, carrying a poise or weight 12, is intermediately pivoted at the point c and has its inner end d in engagement with the bottom 5 at a point between its ends. From this description it will be seen that the weight and the scale-beam serve to hold the bottom D in place against the under side of the weighing-receptacle for closing it.

Located at the upper end of the weighing-receptacle 4 is a suitable knife 2, which is normally held in contact with the stop 3 through the medium of a spring 6, the said knife being here shown as pivotally supported by means of a suitable pin or rod 7.

In the operation of my invention the gathered glass is dropped into the measuring vessel or receptacle until the bottom 5 moves downward slightly, when the unskilled presser, holding the knife 2 to one side of the upper end of the measuring-receptacle, will release the knife, when it will immediately sever the glass, and the predetermined quantity of glass is then within the weighing-receptacle. The bottom 5 is then opened, and the weighed glass drops into the mold 13. The weighing mechanism is then turned to one side of the mold and the plunger or coacting member 14 caused to coact with the mold for forming or partially forming the molten glass which has been delivered thereto through the medium of the weighing mechanism.

By means of a mechanism through the medium of which a predetermined quantity of molten glass can be delivered to the mold I am enabled to materially cheapen the production of the articles made by the machine in that unskilled labor can be employed for the purpose of gathering and pressing in the place of the usual skilled and relatively higher-priced labor required without some means of delivering a predetermined quantity of glass to the mold, and I am also enabled to effect

a saving in the amount of glass, for the reason that by the method now in use it is not possible to always deliver exactly the same quantity of glass to the mold.

5 I here show the measuring mechanism laterally movable; but, as will be readily understood, the mold may be moved laterally in respect to the weighing mechanism, the object of said lateral movement being to permit the 10 plunger or coacting member to coact with the mold. I also show and describe a knife for cutting the glass; but other forms of cutting members, implement, or apparatus may be used without departing from the spirit or 15 scope of my invention.

Having thus described my invention, what I claim, and desire to secure by Letters Patent, is—

1. A machine for the manufacture of glass-
20 ware comprising a forming mechanism, and a weighing mechanism constructed and adapted to deliver to the forming mechanism a predetermined quantity of glass.

2. A machine for the manufacture of glass-
25 ware comprising a mold, a coacting member located in a plane thereabove, and a weighing mechanism located between the mold and its coacting member and constructed to deliver a predetermined quantity of glass to the mold.

30 3. A machine for the manufacture of glass-
ware comprising a mold, a weighing-receptacle situated thereabove, the weighing-receptacle having a knife for cutting the gathered glass, said receptacle constructed to deliver the cut
35 glass to the mold.

4. A machine for the manufacture of glass-
ware comprising a mold, a weighing member situated thereabove and constructed to deliver its contents to said mold, the weighing member and mold being relatively laterally 40 movable.

5. A machine for the manufacture of glass-
ware, comprising a mold, a weighing-receptacle situated thereabove and adapted to deliver its contents to said mold, and a glass-
45 cutting member at the upper end of the weighing-receptacle.

6. A machine for the manufacture of glass-
ware, comprising a mold, and a vertically and laterally movable weighing member located 50 above said mold, and adapted to deliver its contents to said mold.

7. A machine for the manufacture of glass-
ware comprising a mold, a weighing vessel located above said mold, said weighing-receptacle having a laterally and vertically movable bottom.
55

8. A machine for the manufacture of glass-
ware comprising a mold, a receptacle located above the mold, the receptacle having a laterally and vertically movable bottom and a weighing means operatively connected with said bottom to control its vertical movement.
60

In testimony whereof I have hereunto set my hand in the presence of two subscribing 65 witnesses.

CHARLES EDWIN BLUE.
